UNITED STATES PATENT OFFICE.

ALBERT JAMES COOK, OF JERSEY CITY, NEW JERSEY, ASSIGNOR OF THREE-EIGHTHS TO THOMAS MCEWAN, JR., OF SAME PLACE.

ELECTRICAL HAIR-BRUSH.

SPECIFICATION forming part of Letters Patent No. 629,340, dated July 25, 1899.

Application filed April 11, 1899. Serial No. 712,633. (No model.)

To all whom it may concern:

Be it known that I, ALBERT JAMES COOK, a citizen of the United States, residing at Jersey City, in the county of Hudson and State of New Jersey, have invented a new and useful Electric Brush, of which the following is a specification.

This invention relates to an improved electric hair-brush designed specially for the transmission of electric currents to the scalp and roots of the hair in the treatment of this part of the body; and it has for its object to provide a simple, compact, and efficient device of this character that is always ready for use and is thrown into action automatically by the act of grasping the handle for the purpose of using the brush.

A further object of the invention is to construct the brush with all of the parts compactly arranged upon the brush-body, so that the brush will be complete in itself and ready for use at all times without having the usual objectionable dangling wire connections with an extraneous source of electrical energy, while at the same time being so constructed as to constitute not only an electrical hair-brush, but also a complete galvanic medical battery that can be used in the same way as any ordinary medical battery by utilizing the ordinary electrode connections which are commonly used with such batteries.

In carrying out the invention both as a hair-brush and as a medical battery for use with different electrodes, such as sponge electrodes and the like, a further object is to provide a novel arrangement of wiring whereby both the primary and secondary currents may be used singly or in unison, as the requirements of the case may demand.

Another object of the invention is to provide improved means for automatically closing the primary circuit by the simple act of grasping the brush-handle without causing the current to pass through the operator's hand or arm, but compelling the currents to pass through the portions of the body with which the electrodes contact, both where the metal brush bristles or pins constitute the electrodes and where the electrodes are such as are commonly employed in a medical battery.

With these and other objects in view, which

will readily appear as the nature of the invention is better understood, the same consists in the novel construction, combination, and arrangement of parts hereinafter more fully described, illustrated, and claimed.

In the drawings, Figure 1 is a perspective view of an electrical hair-brush embodying the improvements contemplated by the present invention and showing a pair of sponge electrodes connected therewith, whereby the same may be used as an ordinary medical battery. Fig. 2 is a vertical longitudinal sectional view of the brush. Fig. 3 is a bottom plan view thereof, showing the relative arrangement of the three groups of metallic bristles or pins and their respective contact-plates. Fig. 4 is a diagrammatic plan view of the brush, showing all of the circuit-wire connections therefor.

Referring to the accompanying drawings, the numeral 1 designates the brush-back, of the usual configuration and preferably made of suitable non-conducting material, so as not to interfere with the electrical action of the brush, and said back has extended from one end thereof the brush-handle 2. The brush-back 1 has fitted to the under side thereof a series of three metallic contact-plates 3, 4, and 5, respectively, which plates are preferably arranged in parallel relation longitudinally of the brush-back and are suitably insulated from each other, so as to have no metallic connection whatever. While the three contact-plates 3, 4, and 5 are preferably arranged in the manner described, still it will be understood that any other suitable arrangement thereof may be observed, providing that they always maintain the relation of being insulated from each other, so as to have independent contact with the metallic bristles or pins 6 associated therewith.

The metallic brush bristles or pins 6, which project from the brush-back at the under side thereof, are divided into three groups, whereby there will be a separate group of the bristles or pins for each of the contact-plates 3, 4, and 5, and all of the brush bristles or pins 6 have their inner ends fitted in a rubber or equivalent backing-sheet 7, which is also secured to the under side of the brush-back and held over the three metallic contact-plates, so that the heads of the bristles or

pins, at the inner ends thereof, will be in direct metallic contact with the plates, it of course being understood that each group of bristles or pins will only be in contact with its respective plate.

Suitably mounted upon the upper side of the brush-back 1 are a dry-battery cell 8 and an induction-coil 9, which are of any approved type suitable for application to an electrical hair-brush. Both the dry battery and the induction-coil are preferably arranged longitudinally of the brush-back in parallel relation and are fastened thereto by means of suitable brackets 10, which permit of the same being readily removed and replaced whenever necessary. The dry battery 8 is provided at one end with the usual binding-post connections 11 and 12, respectively, for the positive and negative elements of the battery, and the induction-coil 9 is of the usual construction, and essentially consists of the primary winding 13, the secondary winding 14, encircling the primary winding, and a circuit breaker or vibrator 15, arranged at one end of the complete coil. The said coil is also preferably provided with the slidable regulator-sleeve 16, working within the core of the coil and providing means for varying the strength of the current to suit the requirements of the case. The circuit breaker or vibrator 15 of the induction-coil is of the usual type, and the vibrating armature 17 thereof plays between the anvil-plate 18 and the contact-screw 19, with which it is held normally in contact under the influence of the spring.

In carrying out the present invention the circuit is automatically closed through the primary winding of the induction-coil through the medium of a circuit-closing device applied to the handle 2 of the brush. This circuit-closing device essentially consists of a spring pressure-plate 20 and a pair of contact-buttons 21, spaced apart and adapted to be bridged by said plate when pressed thereon. The spaced contact-buttons 21 are fitted in the handle 2 of the brush, with their upper ends projected above the upper surface of the handle and exposed beneath the free end 22 of the spring pressure-plate 20, which end of the said plate is normally sprung out of contact with the button. The spring pressure-plate 20 is arranged longitudinally of the brush-handle, at the upper side thereof, and is secured fast thereto at its outer end by means of the screws or other equivalent fasteners 23. By reason of this arrangement of the pressure-plate it will be obvious that when the operator grasps the handle of the brush the plate is necessarily forced into contact with the buttons 21, so as to close the primary circuit; also, when the hand is released from the brush-handle the pressure-plate springs out of contact with the buttons 21 and thereby automatically opens the primary circuit.

The circuit-closing device is included di-

rectly in the primary circuit between the battery and the primary winding of the induction-coil, the battery-wire *a* having separate portions thereof respectively connected to the separate contact-buttons 21. One terminal of the battery-wire *a* is connected with the binding-post 12 for the negative element of the battery, while its other terminal is connected with the contact-screw 19 of the circuit-breaker. The anvil-plate 18, forming a part of said circuit-breaker, has one terminal of the primary winding 13 connected thereto, and also one terminal of the primary branch *8a* wire *b*, which wire has a connection with the bristle contact-plate 5 and also with a plug-socket 24, fitted in the brush-back for use in connection with separate extraneous electrodes in the manner to be presently explained, and the said plug-socket 24 is arranged for use together with two other similar sockets 25 and 26, respectively, also fitted in the brush-back.

The terminal of the primary winding 13 opposite the connection with the anvil-plate 18 has connected therewith one terminal of the other battery-wire *c*, which wire connects with the binding-post 11 for the positive element of the battery and also has a metallic connection with the plug-socket 25. The binding-post 11 for the positive element of the battery also has connected thereto one terminal of a primary branch wire *d*, the other terminal of which has a connection with the bristle contact-plate 4.

One terminal of the secondary winding 14 of the induction-coil has connected thereto a terminal of the secondary-circuit wire *e*, which wire has a connection with the bristle contact-plate 3 and also with the plug-socket 26. The other terminal of the secondary winding 14 has connected therewith a terminal of the secondary-circuit wire *f*, which wire is not only preferably connected with the binding-post connection for the positive element of the battery but also has metallic connection with the bristle contact-plate 4 and the plug-socket 25, thus completing the wiring of the electrical apparatus.

It will be observed that when the brush is applied to the scalp, so that the latter will close the circuit between the bristle contact-plates 4 and 5, the primary-branch-wire connections *b* and *d*, together with said plates, constitute a parallel or multiple arc connection, so that the primary current not only passes through this connection but also through the primary winding 13 of the induction-coil. It will thus be seen that when the device is used as a brush and the circuit-closer is thrown into operation by the hand of the operator in the manner explained a portion of the current completes a circuit over the wire *a*, the circuit-breaker of the induction-coil, the primary winding 13, wire *c*, including the connection with socket 25, and the positive element of the battery, and also a circuit over the wire *a*, the circuit-breaker of the induc-

tion-coil, the branch wire *d*, plate 5, the scalp, plate 4, and branch wire *d* to positive element of the battery. At the same time a separate and independent circuit for the secondary current is established from one terminal of the secondary winding 14 over the wire *e*, the bristle contact-plate 3, the scalp, the contact-plate 4, the wire *f*, and thence to the other terminal of the secondary winding. In this way not only the galvanic primary current and the secondary current are caused to separately exert their therapeutical influence on the scalp, but by reason of the wiring the effect of these currents is combined at the central plate 4, thus providing in the brush what may be properly referred to as three distinct currents—namely, a primary current, a secondary current, and a primary and secondary current combined.

In using the device solely as a medical battery any type of extraneous electrode may be employed, such as the sponge electrodes shown in Fig. 1 of the drawings. These electrodes have connected therewith the usual conducting-cords 28, carrying the terminal plugs or pins 29, adapted to be inserted in any pair of the several plug-sockets 24, 25, and 26. By inserting the terminal plugs or pins 29 of the electrodes 27, respectively, in the sockets 24 and 25 only the galvanic primary current can pass through the electrodes, while by inserting the plugs or pins 29, respectively, in the sockets 25 and 26 only the secondary or "shocking" current will be directed through the electrodes. The combined effect of the two currents—namely, the primary and secondary—may be secured by fitting the plugs 27 in the sockets 24 and 26, as will be readily determined by tracing out the circuit on diagrammatic view, Fig. 4, of the drawings.

From the foregoing it is thought that the construction, operation, and many advantages of the herein-described electric brush will be readily apparent to those skilled in the art without further description, and it will be understood that changes in the form, proportion, size, and the minor details of construction within the scope of the appended claims may be resorted to without departing from the spirit or sacrificing any of the advantages of this invention.

Having thus described the invention, what is claimed as new, and desired to be secured by Letters Patent, is—

1. In an electrical appliance of the class described, the brush-body having a plurality of groups of metallic bristles insulated from each other, a battery, an induction-coil having its primary winding in circuit with the battery, and separate circuit-wire connections between the primary and secondary windings of the induction-coil and the separate groups of bristles, substantially as set forth.

2. In an electrical appliance of the class

described, the brush-body having a plurality of groups of metallic bristles insulated from each other, a battery, an induction-coil having its primary winding in circuit with the battery, and means for establishing a primary and secondary circuit simultaneously through the separate groups of brush-bristles, substantially as set forth. 70

3. In an electrical appliance of the class described, a brush-body having a plurality of groups of metallic bristles insulated from each other, and means for causing a galvanic primary current and an induced secondary current to pass simultaneously through the 80 separate groups of brush-bristles, substantially as set forth.

4. In an electrical appliance of the class described, the brush-body having a series of three metallic contact-plates insulated from each other, and a separate group of metallic bristles contacting with each of said plates, and means for causing the galvanic primary current and an induced secondary current to pass simultaneously through the several 90 contact-plates and the brush-bristles associated therewith, substantially as set forth. 85

5. In an electrical appliance of the class described, the brush-body having a series of three metallic contact-plates insulated from each other, and a separate group of metallic bristles for each of said plates, a battery, an induction-coil having its primary winding in circuit with the battery, a primary circuit in parallel or multiple arc with a pair of said 100 contact-plates, and a secondary circuit having a wire connection independently with one of said plates and also with a plate having a primary circuit-wire connection therewith, substantially as set forth. 105

6. In an electrical appliance of the class described, the brush-body having a series of three contact-plates insulated from each other, and a separate group of metallic bristles for each of said plates, a battery, an induction-coil, a primary circuit having wire connections in parallel or multiple arc respectively with the primary winding of the coil, and with a pair of said contact-plates, a secondary circuit having an independent wire 110 connection with one of said plates, and also a connection with a plate having a primary circuit-wire connection therewith, and a series of three plug-sockets interposed in the line of the primary and secondary circuit-wire connections for the contact-plates, and adapted to receive the plugs of supplemental or extraneous electrodes, substantially as set forth. 115

In testimony that I claim the foregoing as my own I have hereto affixed my signature in the presence of two witnesses.

ALBERT JAMES COOK.
